COMB FOR THE HAIR

Martin Shaw, Fenham Carr, Lancaster, England

Application September 12, 1932, Serial No. 632,781,
and in Great Britain November 20, 1931

2 Claims. (Cl. 132—11)

This invention comprises a comb which shall provide for parting the hair with facility, as well as being ordinarily useful.

According to the invention a comb has, as well as a plurality of teeth of ordinary size and arrangement, a large broad based tooth of substantially triangular plan. This special tooth is either interposed between a series of ordinary teeth or may be provided at one end of a comb, or perhaps, more than one of such teeth may be provided at suitable positions in the comb. The large tooth is V or substantially V-shaped and has straight or curved edges, which may be smooth or serrated. By virtue of the relative disposition of the large tooth and the neighbouring ordinary teeth, there will be left between the large tooth and an adjacent tooth a V-shaped gap of substantially half the size of the large tooth.

20 The accompanying drawing in Figure 1 shows diagrammatically a comb according to the invention, and in Figure 2 shows a variant of the large tooth.

25 In the drawing A is the back or body of the comb, B the ordinary teeth and C the large broad based tooth which is shown smooth sided or edged in Figure 1 and serrated in Figure 2, its outline in each case being alike. D represents the V-shaped gap between the large tooth and adjacent ordinary teeth.

30 It will be appreciated that the large tooth C may be the end tooth of a comb, in which case, of course, there will be only one gap D.

35 When the comb is drawn through the hair, the large tooth in conjunction with the gaps D, or gap, will automatically part the hair where it passes through. The exact manner of use of the comb is, of course, dependent on individual preference and taste.

40 What I claim is:—

1. In a comb, the combination of a body, a series of relatively closely spaced teeth extending from the body at substantially a right angle thereto, and a relatively broad V-shaped tooth extending from the body in a direction with said first-mentioned teeth and having its major axis extending at a right angle to the longitudinal axis of the body to provide a reversely presented relatively wide V-shaped gap between the V-shaped tooth and an adjacent one of said closely spaced right angular teeth, said gap being defined at one side by an oblique edge of said V-shaped tooth and at its opposite side by one edge of said adjacent right angular tooth and being adapted to freely receive hair deflected laterally by said

V-shaped tooth as said V-shaped tooth parts the hair.

2. In a comb, the combination of a body, a series of relatively closely spaced teeth extending from the body at substantially a right angle 60 thereto, and a relatively broad V-shaped tooth extending from the body in a direction with said first-mentioned teeth and having its major axis extending at a right angle to the longitudinal axis of the body to provide a reversely presented 65 relatively wide V-shaped gap between the V-shaped tooth and an adjacent one of said closely spaced right angular teeth, said gap being defined at one side by an oblique edge of said V-shaped tooth and at its opposite side by one edge 70 of said adjacent right angular tooth and being adapted to freely receive hair deflected laterally by said V-shaped tooth as said V-shaped tooth parts the hair, said oblique edge of said V-shaped tooth being serrated to provide a series 75 of relatively short V-shaped teeth extending into said gap laterally and downwardly toward the free ends of said closely spaced right angular teeth at an acute angle to the major axis of said broad V-shaped tooth. 80
